PLANING MACHINE

Frank H. Jennings, Akron, Ohio, assignor to
National Rubber Machinery Company, Akron,
Ohio, a corporation of Ohio

Application May 5, 1933, Serial No. 669,468

5 Claims. (Cl. 90—31)

This invention relates to planing machines such as are used in the metal-working industry, and the chief object of the invention is to provide an improved machine of the character mentioned 5 capable of planing or smoothing non-planar surfaces. More especially the invention aims to provide planing apparatus capable of planing surfaces that are convex or concave longitudinally, or transversely, or both; and to provide for 10 planing work having a curved or oblique marginal contour. Other objects will be manifest as the specification proceeds.

Of the accompanying drawings,

Figure 1 is a side elevation of a planing machine embodying the invention in its preferred 15 form, and the work therein;

Figure 2 is a fragmentary front elevation thereof, on a larger scale, as viewed from the right of Figure 1;

Figure 3 is a fragmentary rear elevation thereof, on the same scale as Figure 2;

Figure 4 is a section on the line 4—4 of Figure 2; 20 Figure 5 is a section on the line 5—5 of Figure 2; Figure 6 is a plan view of the work; and

Figure 7 is a section on the line 7—7 of Figure 4.

Referring to the drawings, the planing machine embodying the invention comprises a bed 10 having its top formed with the usual slideways 11, 11 for a longitudinally reciprocable table 12, the latter carrying the work 13 that is secured to 15 the table by clamps 14, 14. The under side of the table 12 is provided with a longitudinally extending rack 15 that is meshed with a driving pinion 16, Figures 2 and 3, the latter being driven from the main drive shaft 17 of Figure 1 of the machine. The main drive shaft 17 is belt-driven in the usual manner (not shown) and is provided with the usual reversing mechanism (not shown) whereby its direction of rotation periodically is 20 reversed as the reciprocable table 12 periodically reaches the respective ends of its range of movement.

Near one end of the machine, at each side thereof, is an upright support 20, 20, and extending 25 from one of said supports to the other, above the table 12, is a main cross slide 21, that is constructed and arranged for vertical movement on said supports 20. To this end nuts 22, 22 are secured to said cross slide and have threaded engagement with respective threaded, vertical shafts 23, 23 journaled in the respective supports 20, the front margins of the latter being formed with respective slots 24 whereby the nuts 22 may engage shafts 23 and move upwardly and downwardly thereon. For driving the shafts 23 in

unison, the upper ends thereof, on top of supports 20, are provided with respective bevel gears 25 that mesh with bevel gears 26, 26 mounted upon a transverse shaft 27, and one end of the latter is provided with a gear 28 that is meshed with an idler pinion 29 that is meshed with a driving gear 30. The gear 30 is mounted upon one end of a short shaft 31 that is journaled in a suitable bracket 32 on top of one of the supports 20, the other end of shaft 31 being provided with a driving pulley 33 connected by a belt 34 with a suitable source of power (not shown). The usual clutch mechanism (not shown) is provided with the driving mechanism just described so that the main cross slide may be raised or lowered, upon occasion, as desired.

Secured to the cross slide 21 near the respective ends thereof are vertical brackets 36, 36, each of which has its front face formed with a vertical dovetail slideway 37 for a slide 38 thereon, 20 the slides 38 being connected at their upper ends by a plate 39 having a cam slot 40 formed therein. As is most clearly shown in Figure 7, the brackets 36 are formed with aligned journal bearings for a horizontal shaft 41, and mounted upon the 25 latter, interiorly of each bracket 36, are respective double-thread gear worms 42, 42. Each of the worms 42 performs a similar function so a description of one will suffice for both, attention being especially directed to Figure 4.

Meshed with worm 42 are worm gears 43, 43 that are mounted upon horizontal shafts 44, 44 that are journaled in the bracket 36, above and below the shaft 41 and transversely with relation thereto. The front end of each shaft 44 35 extends through a relatively large orifice 45 in the slide 38, and is provided with a cam 46 that engages a cam-roller 47. The latter is journaled on a short shaft 48 carried by the slide 38 and a yoke 49 secured on the front of said 40 slide. The cams 46 are supplemental cams, the arrangement being such that rotation of the cams raises and/or lowers the slides 38 as a unit. It is this movement of the slides 38 that causes the machine to plane a surface that is longitudinally curved, as subsequently will be described.

At one side of the machine, the left side as viewed in Figures 2 and 7 and the near side as viewed in Figure 1, a change gear bracket 51 is secured to the rear side of main cross slide 21, 50 a part of said bracket constituting a journal for that end of shaft 41. The latter extends through bracket 51 and is provided therewith a gear 52 that is meshed with an idler pinion 53 that in turn is meshed with driving gear 54. The idler 55

pinion 53 is carried upon a quadrant 55 that is adjustably carried on the bracket 51, so that gears 52 of various sizes may be used to change the gear ratio between driving gear 54 and gear 52. Driving gear 54 is mounted upon one end of a shaft 56, Figure 7, that is journaled in bracket 51, the other end of shaft 56 being provided with a bevel gear 57 that is meshed with a bevel gear 58. As is shown in Figure 4, the gear 58 is secured to a sleeve 59 that is journaled in the bracket 51, and said sleeve is splined on a vertical shaft 60, the arrangement being such that the gear 58 will be driven notwithstanding change of elevation of the main cross slide 21.

At its lower end the shaft 60 is journaled in a bracket 61, and is provided with a bevel gear 62 that is meshed with a bevel gear 63 on a counter shaft 64. The counter shaft 64 also carries a gear 65 that is meshed with a gear 66 on the main drive shaft 11, and since the latter periodically reverses its direction of rotation during the operation of the machine, the shaft 41 will similarly reverse. The ratio of the gearing between the main drive shaft 11 and the cams 46 is such that said cams make something less than one revolution during the interval that the table 12 moves from one end of the bed 10 to the other.

Slidably mounted upon the front of the main cross slide 21, intermediate the ends thereof, is a saddle 67, the front face of which is formed with a vertical dovetail guide 68 to receive a slide 69 thereon, the said slide 69 being formed at its upper end with a forked extension 70 that straddles the plate 39, and carries a cam roller 71 that is disposed within the cam slot 40. Mounted upon the front of the slide 69 is a compound slide 72 that is formed with a dowel 73, Figure 5, registering with an aperture 74 in slide 69, the compound slide being retained on slide 69 by a plurality of bolts 75, 75 that have their heads disposed in an annular undercut groove 76 in slide 69. The groove 76 is concentric with dowel 73, the arrangement being such that the compound slide may be positioned at various angles with relation to slide 69. The front face of the compound slide 72 is formed with a vertical dovetail guide 77 that is longitudinally recessed at its center, and a vertically apertured boss 78 is formed on the compound slide above said recess.

A tool slide 80 is slidably mounted on the dovetail guide 77 of the compound slide 72, and carries a bevel gear 81 that is threaded onto a threaded spindle 82 that is disposed between the tool slide and compound slide, being fixedly secured at its upper end in boss 78. Meshed with gear 81 is a bevel gear 83 that has an elongate stem journaled in a suitable bearing structure 84 projecting from the front of the tool slide, said gear stem being provided with a hand-wheel 85 by which the gears may be rotated to raise and/or lower the tool slide with relation to the compound slide.

Mounted upon the front of tool slide 80 is an apron 87, that is arranged for angular adjustment by means of a pivot pin 88, Figure 5, and a pair of retaining bolts 89, 89 that are threaded into the tool slide through an arcuate slot 90 in said apron, said slot being concentric with said pivot pin. Pivotaly mounted upon a horizontal pivot pin 91 on the apron 87 is a clapper block 92, and retained on the front of the latter by suitable clamps 93, 93 is a cutting tool 94. The arrangement of the clapper block 92 is such that the work 13 passes freely under the

tool 94 during the return or inoperative movement of the table 12.

An important feature of the present invention is the provision of means for planing work having an oblique or curved marginal contour. This function of the machine is accomplished automatically by moving the tool laterally during each cutting movement of the work-carrying table. To this end the saddle 67 is constructed so as to embrace a portion of the shaft 41, and splined upon that portion of said shaft is a single-thread gear worm 96. Meshed with worm 96 is a worm gear 97 that is mounted upon a shaft 98 that is journaled in the saddle 67, below the shaft 41 and transversely with relation thereto. The rear end of shaft 98 projects beyond its bearing and is provided with a cam 99.

The cam 99 is engaged at two diametrically opposite points on its periphery by cam followers consisting of rollers 100, 100 that are journaled on respective arms of a bracket 101, and the latter is pivotally mounted at 102 upon a slide 103 that is slidably mounted in a guide 104 that is mounted upon the top of main cross slide 21. Set screws 125, 125 normally hold the bracket 101 in the operative position shown on the slide 103. The gear ratio controlling the cam shaft 98 is such that the cam 99 makes somewhat less than one revolution during each cutting movement of the table 12, and returns to point of starting during the return movement of said table. Since the cam followers occupy fixed positions, rotation of the cam causes lateral movement of the saddle 67 and tool 94 carried thereby whereby arcuate or oblique planing is accomplished. If it should be desirable, upon occasion, to operate the machine without effecting lateral movement of the tool 94 during the cutting operation, the cam 99 may be removed, and by removing set screws 125 the bracket 101 may be tilted rearwardly to a position at 90° to that shown, whereby it will not interfere with periodic indexing of the cutting tool intermediate each cutting operation.

The guide 104 is provided with end brackets 105, 105 and carried therein is a screw 106 that threads through the slide 103. At one end the screw 106 is provided with a gear 107 that is meshed with a gear 108 on the end of an operating rod 109, the latter being journaled in a bracket 105, and in a bracket 110 secured to one end of the main cross slide 21. The arrangement is such that manual rotation of rod 109 moves the slide 103 along guide 104. For locking the slide 103 in fixed position on guide 104, there is a tapered gib 111, Figures 5 and 7, between the interfitting dovetail portions of the said slide and guide, said gib being provided with an operating rod 112 that is connected to one arm of a bell crank 113 that is pivotally mounted at 114 on a lateral extension of the bracket 110, the other arm of the bell crank constituting an operating lever. Thus upon loosening of the gib 111 the tool 94 can be moved laterally by manually rotating the rod 109. This is done periodically after each cutting movement of the machine, the gib being tightened before the succeeding cutting movement commences.

When, as previously described, it is not desired to move the tool laterally during the cutting operation, and the cam 99 is therefore removed, the following means is provided for indexing the tool laterally between cutting operations. A screw 116 extends from end to end of the main cross

slide 21, being threaded through a nut 117 that is secured to the rear face of the saddle 67 (see Figure 5). As is shown in broken lines in Figure 2, one end of screw 116 extends freely through 5 the end wall of cross slide 21 and is provided with a removable collar 118. The other end of said screw extends freely through the other end wall of the said slide, and is provided with a gear 119, Figure 7, that meshes with one of the gears 120, 10 121 for driving the screw 116 in the usual manner, intermittently to index the cutting tool between cutting operations. When the tool is to be moved laterally during cutting, and is under control of cam 99, the screw 116 is in the position 15 shown in full lines in Figure 2, its left end being withdrawn some distance from its bearing in the cross slide, and the gear on its right end being out of engagement with the gears 119, 120. In this position the screw moves freely with the 20 movement of the tool.

In the operation of the machine, the work 13 is clamped to the table 12 in the usual manner, and the proper cams 46, 39 and 99 are mounted on the machine to control the planing of the work 25 to proper contour. The machine is then set in motion and the table 12 reciprocates in the usual manner to move the work past the cutter 94 in operative relation thereto. The cams 46, operating in timed relation to the movement of the 30 table 12, raise or lower the structure comprising slides 38 and cam plate 39, and thus raise or lower slide 69 that is connected to the latter, with the result that the tool 94 is raised or lowered during each cutting operation and a longitudinally 35 curved cut is made on the work as is most clearly shown in Figures 1 and 5. The tool 94 is indexed laterally between cutting operations, and the cam groove 40 in plate 39 controls the depth of cut, so that by using the proper cam a transversely curved planing of the work may be effected 40 as is most clearly shown in Figures 2 and 3.

The function of the cam 99 is to move the tool obliquely during the cutting operation and thus to plane a surface that is oblique to the movement of the work. The work shown in the drawings has such an oblique surface along only one margin thereof so that this cam may be adjusted so as to be inoperative during a part of the planing operation, in which case the tool will be 45 automatically indexed after each cutting stroke by the screw 116. When the cam 99 is operative, the screw 116 is inoperative and the tool is manually indexed by means of the screw 106.

The machine is mainly automatic in its operation, and is capable of planing a large number 55 of intricate shapes. The feature of utilizing cams for effecting the various movements of the tool is advantageous in that it allows the tool to be moved at varying and non-uniform speeds in any direction, or to dwell in one place if desired, which

result it is impractical to attain by the use of screws or gears alone. The use of a reciprocating table for supporting the work assures that the latter is fed to the tool at a constant uniform speed. This feature of the invention is advantageous as compared to apparatus using rotary tables wherein the surface speed of the work varies in proportion to its distance from the axis of the table and thus creates another factor to be considered in designing mechanism to operate the 10 tool.

Modification may be resorted to without departing from the spirit of the invention or the scope of the appended claims, which are not limited wholly to the specific construction shown 15 and described.

What is claimed is:

1. In a planing machine, the combination of a reciprocable table for the work, a cutting tool for operating upon the work, a movable support 20 for said tool, a reversible rotatable shaft driven in timed relation to the operation of the table, respective cam means controlled by said shaft for concurrently effecting non-uniform vertical and lateral movements of the tool support during a 25 cutting operation, and means for indexing the tool support laterally between successive cutting operations whereby each cutting operation is begun at a position laterally of the preceding cut.

2. In a planing machine, the combination of 30 a reciprocable table for the work, a tool for operating upon the work, a vertically movable slide carrying the tool, a laterally movable support for said slide, a rotatable cam carried by said support, means for rotating said cam and reversing the same in timed relation to the movement of the table, and a stationary cam follower 35 engaging the said cam whereby rotation of the latter effects lateral movement of the tool support.

3. A combination as defined in claim 2 including means for laterally indexing the cam follower.

4. In a planing machine, the combination of a reciprocable table for the work, a tool for operating upon the work, a laterally movable support 45 upon which the tool is mounted, a rotatable cam carried by said support, means for rotating said cam and reversing the same in timed relation to the movement of the table, cam rollers engaging said cam, a normally stationary bracket 50 carrying said rollers, a screw threaded through said bracket, and means for rotating said screw between cutting operations so as to advance the support laterally a determinate distance in one direction.

5. A combination as defined in claim 4 including means for tilting the cam roller bracket so that the rollers thereon are positioned out of their normal operative position.

FRANK H. JENNINGS. 60
